(57) **CLAIM**

The ornamental design for a cutter, as shown and described.

DESCRIPTION

This application is related to U.S. patent application Ser. No. 13/228,394, entitled "Ergonomic Cutter" filed herewith, U.S. patent application Ser. No. 13/228,399, entitled "Cutter and Safety Holster System" filed herewith, U.S. patent application Ser. No. 13/228,408, entitled "Safety Cutter with Improved Blade Deployment Mechanism" filed herewith, U.S. patent application Ser. No. 13/228,413, entitled "Safety Cutter with Improved Blade Locking Mechanism" filed herewith, U.S. patent application Ser. No. 13/228,416, entitled "Safety Cutter with Improved Blade Depth Adjustment Mechanism" filed herewith, U.S. patent application Ser. No. 13/228,417, entitled "Safety Cutter with Improved Blade Change Mechanism" filed herewith, U.S. patent application Ser. No. 13/228,418, entitled "Safety Cutter with Improved Blade Storage Mechanism" filed herewith.

FIG. 1 is a perspective view of a cutter showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings show features of the cutter that are included for illustrative purposes only and form no part of the claim.

1 Claim, 6 Drawing Sheets
